UNITED STATES PATENT OFFICE.

ANDREW J. SAGER, OF WINCHESTER, VIRGINIA.

CONE TIMER FOR INTERNAL-COMBUSTION ENGINES.

Application filed December 28, 1922. Serial No. 609,435.

To all whom it may concern:

Be it known that I, ANDREW J. SAGER, citizen of the United States, residing at Winchester, in the county of Frederick and 5 State of Virginia, have invented certain new and useful Improvements in Cone Timers for Internal-Combustion Engines, of which the following is a specification.

My invention relates to a cone shaped 10 timer or commutator for internal combustion engines, and one of the objects of the invention is to provide such a device which on account of its conical shape will give a firm contact between the relatively movable 15 conducting parts and thereby provide a full spark.

While my invention is of general application and can be applied to any internal combustion engine, it is shown herein in 20 connection with the type used in the Ford automobile.

The timer which is at present in use on Fords is a four contact one, mounted at the front end of the cam shaft, one contact being provided for each cylinder. The cam 25 shaft carries a revolving roller which completes the circuit through contact segments embedded in a ring of fiber which is retained in the casing. With use, the segments become scalloped due to the jumping and wear of the roller, and accordingly a firm contact between the conducting parts 30 is not secured. The timer also has a tendency to become gummed up in cold weather leading to further poor contacts.

With the object of overcoming the defects of the customary Ford type of commutator, which become accentuated in operation due to the low tension current employed, I have devised what I designate as 40 a "cone timer."

Referring to the drawings for a more complete disclosure of the invention,

Figure 1 is an inside elevation of the 45 timer, the cam shaft being shown in section;

Fig. 2 is a section on the line 2—2 of Fig. 1;

Fig. 3 is a perspective view of the brush 50 plate and brush;

Fig. 4 is a section on the line 4—4 of Fig. 2;

Fig. 5 is a perspective view of the cone timer removed from the cam shaft.

In the drawing, 1 is the casing of the 55 timer, and fixedly secured inside of the same is a ring 2 of insulating fiber, in which the plates 3 are held by means of the T head bolts 4, which also serve to conduct the 60 generated current.

Fixedly mounted on the cam shaft 5 is a collar 6 carrying a cone shaped member 7 made of insulating fiber. Secured in the said collar and cone is a single contact point 8, in permanent conductive contact with 65 the shaft 5 at one end, and from time to time, with the metal brushes 9, at the other extremity.

Each brush is detachably secured in position to permit of ready replacement of worn 70 out brushes. The brushes 9 are detachably and slidably mounted on leaf springs 10 by means of a tongue and groove connection as shown in Fig. 4, an abutment 11 carried by the brushes limiting the inward movement thereof.

The leaf springs and brushes fit into recesses 12 in the fiber ring 2, the plates 3 forming a lining for the recesses. One arm of the leaf spring is interposed between the 80 bottom of the plate 3 and the bottom of the recesses 12 and is clamped securely in place by the bolt 4.

By using a cone shaped timer, it will be seen that it can be readily slipped into position. With the step of placing it in position, the leaf springs are put under compression so that the brushes are held firmly 85 in contact with the cone 7.

From the above description it will be apparent that I have produced a device of the character enumerated as desirable, and while I have illustrated and described the preferred form of the invention, it will be understood that I reserve the right to all 90 changes falling within the spirit and scope of the appended claims.

What I claim as new and desire to secure by Letters Patent of the United States is:

1. A cone timer for internal combustion 100 engines comprising a rotary cone shaped member carrying a conducting point, a casing, an insulating ring fitting into the casing and provided with a plurality of radial

recesses and leaf springs carrying brushes closely fitting the said recesses.

2. A cone timer for internal combustion engines comprising a rotary cone shaped member carrying a conducting point, a casing, an insulating ring fitting into the casing and provided with a plurality of radial recesses, metal plates forming a lining for

the said recesses, leaf springs carrying brushes closely fitting the said recesses, headed bolts for securing the leaf springs in position in the said recesses, the said bolts serving to conduct the generated current. 10

In testimony whereof I affix my signature.

ANDREW J. SAGER
